US00D959401S

(12) **United States Design Patent** (10) **Patent No.:** **US D959,401 S**
(45) **Date of Patent:** **** Aug. 2, 2022**

(54) **MOBILE PHONE**

(71) Applicant: **BEIJING XIAOMI MOBILE SOFTWARE CO., LTD.**, Beijing (CN)

(72) Inventors: **Chunhou Zheng**, Beijing (CN); **Yu Chen**, Beijing (CN); **Shaowei Guo**, Beijing (CN); **Yang Bai**, Beijing (CN); **Chuanyu Li**, Beijing (CN); **Wencheng Liu**, Beijing (CN); **Haotian Kou**, Beijing (CN); **WeiQi Huang**, Beijing (CN)

(73) Assignee: **Beijing Xiaomi Mobile Software Co., Ltd.**, Beijing (CN)

(**) Term: **15 Years**

(21) Appl. No.: **35/511,303**

(22) Filed: **Jan. 15, 2021**

(80) **Hague Agreement Data**

Int. Filing Date: **Jan. 15, 2021**

Int. Reg. No.: **DM/212404**

Int. Reg. Date: **Jan. 15, 2021**

Int. Reg. Pub. Date: **Feb. 5, 2021**

(30) **Foreign Application Priority Data**

(57) **CLAIM**

The ornamental design for a mobile phone, as shown and described.

DESCRIPTION

1.1 is a front elevation view of a mobile phone showing our new design;

1.2 is a back elevation view thereof;

1.3 is a left side elevation view thereof;

1.4 is a right side elevation view thereof;

1.5 is a top plan view thereof;

1.6 is a bottom plan view thereof; and

1.7 is a perspective view thereof.

The broken lines are included for the purpose of illustrating portions of the mobile phone that form no part of the claimed design.

1 Claim, 7 Drawing Sheets
